LATHER HEATER

Franklin C. Farnam, 19 Glenview Road,
Asheville, N.C. 28804

Filed May 13, 1975, Ser. No. 575,692

Term of patent 14 years

Int. Cl. D9—01

U.S. Cl. D6—95

FIG. 1

FIG. 2

FIG. 3

FIG. 1 is a top perspective view of a lather heater showing my new design;

FIG. 2 is a bottom perspective view thereof; and

FIG. 3 is a side elevational view taken from the left of FIG. 1, the upper portion of an aerosol can being shown in broken lines for illustrative purposes only.

I claim:

The ornamental design for a lather heater, substantially as shown and described.
